UNITED STATES PATENT OFFICE.

EMORY D. NICHOLS, OF CHICAGO, ILLINOIS.

PENHOLDER.

1,407,563.

Specification of Letters Patent. Patented Feb. 21, 1922.

Application filed August 18, 1919. Serial No. 318,073.

To all whom it may concern:

Be it known that I, EMORY D. NICHOLS, a citizen of the United States, and a resident of Chicago, in the county of Cook and State of Illinois, have invented certain new and useful Improvements in Penholders, of which the following is a full, clear, and exact description.

The invention relates to pen-holders and its object is to provide readily releasable means for securing the pen-point in the socket of the pen-holder.

The invention consists in the several novel features hereinafter set forth and more particularly defined by claims at the conclusion hereof.

In the drawings: Fig. 1 is a longitudinal section of a pen holder embodying the invention, the pen-gripping device being shown in operative position. Fig. 2 is a similar view showing the gripping device while it is released. Fig. 3 is a perspective of the gripping device and Fig. 4 is a perspective of the socket.

The invention is illustrated in connection with a pen holder comprising a handle 5 recessed at one end to receive a socket 6 which is preferably formed of sheet metal and is longitudinally split and resilient so that it will frictionally secure itself in the recess. My improved pen holding or gripping device is preferably formed of a single piece of sheet metal and comprises a shank 7, the rear end of which is provided with tongues bent in opposite directions from the shank to form semi-circular spring portions 8 which are adapted to clampingly engage in the socket 6. To firmly secure the gripping device in the socket the upper tongue 8 is indented to provide a pocket 9 and the socket is indented to form a projection 9' for engaging in the pocket.

Along its outer section the shank 7 has its sides deflected upwardly and inwardly to form substantially quarter-circular resilient seats or jaws 10 for receiving the pen point 11 at its inner side. The outer end of the shank is deflected downwardly and rearwardly to form the sections 12 and 14. The section 12 at its sides is deflected rearwardly to provide the triangular shaped latch tongues 13.

The clamping structure is preferably of comparatively thin tempered steel so as to be resilient in all its parts. When it is inserted in the socket 6 the shank 7 engages

with the outer edge of the socket at the bottom thereof and at the base of the triangular tongues 13. The pen point is then inserted between the roof of the socket and the jaws 10, whereupon upward pressure is applied on the section 14. This pressure will cause outward swing of the section 12 as the inclined rear edges of the tongues 13 pass along the edge of the socket, and when the bases of the triangular tongues arrive above the edge of the socket, the resiliency of the material will cause the section 12 to swing inwardly to carry the bases of the tongues into contact with the floor of the socket. Upward pressure on the section 14 will also securely clamp the pen point between the jaws 10 and the roof of the socket and then when the triangular tongues are in locking engagement with the floor of the socket, such clamping engagement of the pen will be maintained. When it is desired to remove the pen point outward pressure is applied on the section 14 until the tongues are disengaged from the floor of the socket whereupon the resiliency of the shank will again swing the outer section of the shank downwardly to the position shown in Fig. 2 to separate the jaws 10 from the roof of the socket so that the pen point can be readily extracted.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a pen holder, the combination of a handle having a recess, a socket secured in said recess, and a pen securing device comprising a resilient shank, means for securing said shank at its inner end in said socket, jaws on the outer end of said shank for cooperating with the roof of said socket to receive a pen point, a downwardly extending section adjacent the outer end of said shank, inwardly extending latch projections on said downwardly extending section, said securing device being of resilient material and said shank being normally held down with said latch projections below the floor of said socket at the outer edge thereof, upward pressure on said downwardly extending section causing said latch projections to be raised above the floor of said socket and to

- be sprung inwardly to engage against the top of said floor, said upward pressure causing bending of said shank to clamp a pen point between said jaws and the roof of said socket and said latches holding said jaws in raised clamping position.
2. In a pen holder, the combination of a handle having a recess in its end, a socket secured in said recess, and a pen securing device comprising a shank of resilient material, means for securing said shank at its inner end in said socket, the outer end of said shank being deflected downwardly, triangular shaped latch tongues deflected inwardly from said downwardly extending section, the resiliency of said shank normally holding said latch projections below the floor of said socket, upward pressure on said downwardly extending section causing said latch projections to glide along the edge of said socket to eventually be sprung inwardly to engage against the top of the socket floor to thereby hold said shank in its upper position, and resilient jaws extending upwardly from said shank between which and the roof of said socket a pen point is clamped when said shank is raised into latched position.
3. In a pen holder, the combination of a handle having a recess in its outer end, a socket secured in said recess, and a pen securing device constructed integrally of resilient sheet metal, said device comprising a shank extending through said socket, means for securing said shank at its end in said socket against longitudinal movement therein, the outer end of said shank being deflected downwardly past the floor of said socket, latch projections extending rearwardly from said downwardly deflected section, the resiliency of said metal normally holding the outer section of said shank down with said latch projections below the floor of said socket, upward pressure on said downwardly deflected section causing said latch projections to glide past the edge of said socket and into position above the floor of the socket to lock said shank in raised position, and resilient jaws formed on top of the outer section of said shank, said jaws serving to receive a pen point and to clamp said point against the roof of said socket when the outer shank section is raised and latched in raised position.
4. In a pen holder, the combination of a handle having a recess in its end, a socket secured in said recess, and a pen securing device constructed from a single piece of resilient sheet metal, means for securing said shank at its inner end in said socket against longitudinal movement therein, the outer section of said shank normally deflecting downwardly against the floor of said socket, a downwardly extending section at the outer end of said shank, triangularly shaped latch tongues deflected inwardly from the side of said downwardly extending section, upward pressure on said downwardly extending section causing said latch tongues to glide along the edge of said socket to be eventually sprung inwardly by the resiliency of the metal to engage against the inner side of the floor of said socket whereby to hold said shank in raised position, and resilient extensions on top of the outer section of said shank forming clamping jaws between which and the roof of said socket a pen point is clamped when the outer section of the shank is raised and latched.
5. In a pen holder, the combination of a handle having a recess, a socket secured in said recess, and a pen securing device constructed from a single piece of resilient sheet metal, said device comprising a shank extending through said socket, means for rigidly securing the inner end of said shank in said socket to hold said shank against longitudinal movement therein, the outer section of said shank being normally inclined downwardly, a downward extension at the outer end of said shank, triangularly shaped latch tongues deflected rearwardly from the sides of said downwardly extending section, the end of said downwardly extending section being deflected laterally to form a finger section, upward pressure on said finger section causing said downwardly extending section to be raised and said latch tongues to be forced past the outer edge of said socket and eventually into engagement with either side of the floor of said socket whereby the outer section of said shank will be held in upper position, and resilient jaws formed on top of the outer section of said shank between which jaws and the roof of said socket a pen point is rigidly clamped when said outer section of the shank is raised and latched, outward pressure against said finger section causing said latch tongues to be released from said socket whereby the resiliency of the metal will swing the outer section of the shank downwardly to release the clamping jaws from the pen point.

EMORY D. NICHOLS.
